[57] CLAIM

The ornamental design for a container, as shown and described.

DESCRIPTION

FIG. 1 is a perspective view of a container showing our new design;

FIG. 2 is a front elevational view thereof, the rear view being a mirror image thereof;

FIG. 3 is a side elevational view thereof, as viewed from the left of FIG. 2;

FIG. 4 is a side elevational view thereof, as viewed from the right of FIG. 2;

FIG. 5 is a top plan view thereof;

FIG. 6 is a bottom plan view thereof;

FIG. 7 is a perspective view similar to FIG. 1, but showing another embodiment; and,

FIG. 8 is a top plan view thereof.
